Inventor
Ernest L. Plass

By Watson E. Coleman
Attorney

UNITED STATES PATENT OFFICE.

ERNEST L. PLASS, OF ELMHURST, ILLINOIS.

SUPPORT.

Application filed June 17, 1924. Serial No. 720,628.

To all whom it may concern:

Be it known that I, ERNEST L. PLASS, a citizen of the United States, residing at Elmhurst, in the county of Du Page and 5 State of Illinois, have invented certain new and useful Improvements in Supports, of which the following is a specification, reference being had to the accompanying drawings.

10 This invention relates to supports and more particularly to a support adapted for use in the formation of benches, tables and the like.

An important object of the invention is to 15 provide a device of this character which may be readily set up and which accordingly is particularly adapted for use in the erection of temporary seats, picnic tables and the like.

20 A further object of the invention is to provide a device of this character which may be very cheaply produced, being formed from a single strip of sheet iron, and which provides a relatively broad and solid base 25 in use.

These and other objects I attain by the construction shown in the accompanying drawings, wherein for the purpose of illustration is shown a preferred embodiment of 30 my invention and wherein:—

Figure 1 is a side elevation showing standards constructed in accordance with my invention employed to hold a plank forming a seat;

35 Figure 2 is a section taken at right angles to the view in Figure 1;

Figure 3 is a perspective of one of the standards removed.

Referring now more particularly to the 40 drawings, the standard is formed from a single strip of metal, the central portion of which is slightly bowed upwardly to provide a base 10. In the ends of this base the metal of the ends of the strip 45 are bent upwardly and inwardly to form side members 11 and the upper ends of these side members are vertically extended for a short distance, as indicated at 12. At the ends of these vertical portions 50 the strip is inverted and brought downwardly vertically, as indicated at 13, one of these downwardly extending strips 13 being provided with an angular foot 14 directed toward the other of the strips and

resting upon the upper surface of the base 55 10. The other of the vertical portions 13 is provided with an angular foot 15 directed toward the remaining angular strip and resting upon the upper surface of the foot 14. Through the overlapping feet 14 and 15 60 and through the base an opening is formed, indicated at 16, through which is directed a bolt 17 securely holding the portions in engaged position. Through the abutting portions of the vertical portions 13 and 12 65 aligned openings 18 are formed through which are directed bolts 19 having thumb nuts 20 upon the threaded ends thereof.

In the use of the device a plurality of the supports are employed vertically with a 70 horizontal support 21, this support being formed from a length of 2 x 4" or other suitably sized material having openings 75 formed therethrough for the reception of the bolts 19 at proper intervals. Supports of this character can be arranged at spaced points and a seat 22 placed thereacross. It will be obvious that by employing two of the vertical supports of the proper height and a horizontal support 21 of the proper 80 length a saw-horse will be formed. It will further be obvious that a support of this character is capable of practically unlimited application. It will be obvious that this support, being made from a single strip of 85 sheet metal, may be very cheaply produced and at the same time will provide a rigid and durable device for this purpose.

I claim:—

1. A support of the character described 90 comprising a base, vertical portions centrally above and spaced from the base, braces connecting the vertical portions and the base at the ends of the base, other braces 95 extending vertically between the vertical portions and the base at the center thereof, the vertical portions having securing elements extending therethrough and adapted for engagement with a member to be supported, the vertical braces having portions overlapping one another and the base, and a single securing element extended through such overlapping portions and base and securing the same together.

2. A support of the character described 100 comprising a single strip of metal having its central portion bowed upwardly, the ends of the bowed portion being bent upwardly

and inwardly above the bowed portion to form side members, the upper ends of the side members being vertically extended, the strip at the ends of said vertical portions being inverted and extended downwardly vertically for engagement with the base, the terminal portions of the inverted portions

being provided with angular feet engaging the base and one another, and a securing element directed through the base and such angular feet. ¹⁰

In testimony whereof I hereunto affix my signature.

ERNEST L. PLASS.
